UNITED STATES PATENT OFFICE.

MYER M. MARBEL, OF CHICAGO, ILLINOIS.

SURGICAL INSTRUMENT.

Application filed July 6, 1925. Serial No. 41,504.

To all whom it may concern:

Be it known that I, MYER M. MARBEL, a citizen of the United States, and a resident of the city of Chicago, county of Cook, and 5 State of Illinois, have invented certain new and useful Improvements in Surgical Instruments, of which the following is a specification.

My present invention relates to surgical 10 instruments, more particularly to surgical instruments for use in performing sewing operations such as sewing together the parts of cuts, incisions, gashes and the like, and my invention has for its main object the 15 provision of an improved combined instrument of this character which will embody certain desired features of simplicity, efficiency and convenience.

Another object is to provide a surgical 20 instrument of this character comprising a compact combination of the various instruments usually employed in sewing operations; which will enable a saving in time and labor, tend to avoid confusion, induce confidence 25 and allay nervousness on the part of the operator; and which will in general enable sewing operations to be performed at greater speed and with increased skill.

Other objects will appear hereinafter. 30 The invention consists in the combinations and arrangements of parts hereinafter described and claimed.

The invention will be best understood by reference to the accompanying drawings, 35 forming a part of this specification, and in which,

Fig. 1 represents a plan view of my improved instrument;

Fig. 2 is a fragmental view with a part of 40 the tank holder shown in section;

Fig. 3 is an enlarged detail view illustrating in particular the needle threading means combined with the feeding piece;

Fig. 4 is a similar view but showing how 45 the stitching material is looped and applied in connection with the needle threading means for threading the needle;

Fig. 5 is a detail showing the needle as it appears when threaded;

50 Figs. 6 to 10 are progressive views showing the steps involved in sewing the parts of an incision together and knotting the stitching material;

Fig. 11 is an exaggerated view of a type 55 of double knot that may be produced;

Fig. 12 is a fragmental view showing the use of the instrument in severing the sewing material after the knot has been completed;

Figs. 13 and 14 represent other types of 60 instruments in connection with which my improvements may be employed.

The preferred embodiment of my invention, as illustrated in the accompanying drawings, comprises two blades 15 and 16 65 movable on a pivot 17 by which they are held together, said blades having cooperating cutting edges 18 and 19, and also having cooperative roughened jaws 18' and 19'. The blade 15 is made with a thumb receiving 70 eye 20 and the blade 16 with a finger receiving eye 21, so that this structure may be conveniently used like a pair of scissors in cutting the stitching material with the cooperative jaws 18 and 19, and in holding 75 the sewing needle with the roughened jaws 18' and 19', and in variously manipulating the structure for effecting the sewing operations and tying the stitching material into knots. One of the arms, herein shown as the 80 arm 15 may be provided with a toothed projection 22, while the other blade 16 is formed with a hooked member 23 adapted to operate with the toothed projection for the purpose of holding the roughened jaws 18' 85 and 19' clamped upon the sewing needle with the degree of rigidity desired.

In this form of construction for the needle holder, I secure to the thumb eye 20 a tank holder 24 of cylindrical form and having an 90 open end. Within this tank holder is disposed a glass vessel, preferably in the form of a bottle 25, the length of the bottle with respect to that of the tank holder being preferably such that the bottle will protrude 95 slightly beyond the open end of the tank holder in order readily to be grasped for application and removal. This bottle is fitted with an enclosure comprising a feeding plug 26 for the stitching material, of which a roll 100 27 (Fig. 2) is disposed within the bottle in any suitable sterilizing liquid or medium. The plug or feeding piece 26 is preferably made of hard rubber so as to effect a tight seal and so that the line of the stitching material as 28 may be suitably taken therethrough as needed for the stitching operations. This is preferably accomplished by threading the stitching material on a needle 105 and piercing the feeding piece 26 with the 110

needle so as to carry a line of the stitching material therethrough. By means of this arrangement a roll of the stitching material is kept in proper sterilized condition within the holder, and an end of the line 28 is also available exteriorly of the tank holder, while the line of material in the feeding piece is frictionally held, the rubber material of the feeding pipe affording liquid-tight engagement with the line of stitching material.

This plug or feeding piece 26 carries a sewing needle 29, a needle threader 30 and a clamping member 31 for suitably clamping the stitching material while the needle is being threaded on the needle threader 30. To thread the needle a loop A (Fig. 3) is formed from the stitching material, and this loop is engaged over the needle threader 30 subsequently to the application on the needle threader of the sewing needle 29 (Fig. 4). After the loop A is applied to the needle threader, the line of sewing material doubled upon itself (Fig. 4) is clamped in the clamping member 31. Thereupon the needle is withdrawn from the needle threader and over the loop A so as to be threaded upon the stitching material as best illustrated in Fig. 5.

The threaded needle is thereupon secured between the jaws 18' and 19' and applied to the edges of an incision as 32 which is to be sewed up. A loop B is then formed and slipped upon the sewing needle which is then drawn entirely through the edges of the incision. The loop B is then tightened so as to form a knot C at the connected edges of the incision (Fig. 7). From the reserve material in the holder, there is then drawn through the feeding piece a supply of sewing material sufficient to form a loop D through which is passed the sewing needle and a portion E of the sewing material. By doing this a new loop F is produced through which the needle with the portion E attached thereto is drawn by a forward movement of the needle holder as shown in Fig. 10. This step in the operation serves to close the loop B. Thereupon the sewing needle is removed from the jaws of the instrument and the line of sewing material is drawn in opposite directions as indicated by the arrows G and H (Fig. 11) thereby forming a second knot I (Fig. 12). Having thus formed the knots and drawn them tightly for securing the edges of the incision 32 together the sewing material is severed from the knots by the cutting edges 18 and 19. Each time, therefore, the sewing needle is passed through the edges of the incision, two securing knots are made and drawn tightly after which the sewing material is separated from the knot in order to rethread the needle for the sewing of the next stitch. The needle holder is held in the right-hand (if the user be right-handed) during the entire

time the stitching and other operations are performed, the left hand being always free for threading the needle, making the loops and for use in other activities during the sewing operation. With a little practice in the use of this improved instrument an operating surgeon becomes very skillful with the result that he is able to sew more rapidly, producing a great many more stitches per minute than when working under the usual conditions where the sewing material must be located at one place, the sewing needle at another place, and under conditions where formation of the loops for the knots must be made entirely by hand in separate lines or strings without having the advantage of the adjacent continuous line of sewing material as provided in the present invention. From the use of this improved instrument, other advantageous results also flow: Namely, there is no confusion in locating the instruments; the sewing thread is employed at once upon its removal from the anesthetic therein; less assistance by way of attendants is required; the flow of blood is stopped quicker; tighter knots are insured; and the operating surgeon in view of these various conditions is able to perform his work with less nervousness. Adverting to the tank holder, it will be observed that the same is provided with a projecting flange 33 having a laterally projecting pin 34. Adapted to cooperate with this flange in order to inclose the feeding piece with the various parts carried thereby, is a cap 35 provided with a bayonet slot 36 for the suitable reception of the pin 34. While I have herein shown and described a tank in the form of a bottle 35 as inserted in the tank holder 34, it will be obvious that, if found desirable, the tank holder itself may be employed as the tank or well for the materials to be carried, although the form illustrated and described is preferred since it permits of the ready application and removal of a bottle as 25.

In Figs. 13 and 14 I illustrate how the tank holder may be applied to needle holding instruments as 36 and 37, respectively. In each of these instances, due to the expansion of the blades, which are without thumb and finger receiving eyes and which are manipulated by being embraced by the hand in a manner that will be readily understood, the tank holder is secured to the inner side of one of the blades as shown.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A surgical instrument including a pair of pivotally connected blades characterized by having means for holding a needle and cutting stitching material; a tank holder for stitching material on one blade and a needle threader arranged in relation to said tank, substantially as described. 45
2. A surgical instrument including a pair of pivotally connected blades characterized by having means for holding a needle and cutting stitching material; a tank holder for stitching material on one blade; a plug removably fitting said holder and constituting a feeding piece for the withdrawal of the stitching material and a cap enclosing said plug and engaging said holder, substantially as described. 50
3. A surgical instrument including a pair of pivotally connected blades characterized by having means for holding a needle and cutting stitching material; a tank holder for stitching material on one blade; a feeding piece for the holder; and needle threading means arranged on said feeding piece, substantially as described. 55
4. A surgical instrument including a pair of pivotally connected blades characterized by having means for holding a needle and cutting stitching material; a tank holder for stitching material on the blade; a stitching material feeding piece; a member for threading the needle; and a member for holding the thread during the threading of the needle, substantially as described. 60
5. A surgical instrument including a pair of pivotally connected blades characterized by having means for holding a needle and cutting stitching material; a tank holder for stitching material on one blade and a needle threader arranged in relation to said tank, substantially as described. 65

cutting stitching material; a tank holder for stitching material on one blade; and a plug constituting part of the tank holder and adapted to be pierced by a needle for the withdrawal of stitching material there-through, substantially as described.

6. A surgical instrument including a pair of pivotally connected blades characterized by having means for holding a needle and cutting stitching material; a tank holder for stitching material on one blade; a stitching material feeding piece in the holder; means for threading a needle arranged on said feeding piece; and a cap engageable with the holder for enclosing said feeding piece and needle threading means, substantially as described. 70

7. A surgical instrument including two blades held together by a pivot; a tank on one blade for holding sterilizing liquid and stitching material; a removable feeding piece forming a closure for the tank and having a passage through which the stitching material may be taken as needed for co-operation with the blades to effect stitching operations, substantially as described. 75

8. A surgical instrument including two blades held together by a pivot; a tank on one blade for holding sterilizing material and stitching material; a removable feeding piece forming a closure for the tank and having a passage through which the stitching material may be taken, needle threading means carried by said feeding piece; and a cap engageable with the tank and enclosing the feeding piece and needle threading means, substantially as described. 80

In testimony whereof I have signed my name to this specification.

MYER M. MARBEL.
